 New York, N. Y., a corporation of New York

Application January 18, 1949, Serial No. 71,502

11 Claims. (Cl. 250—27)

1

The present invention relates to pulse generating systems and has for its main object the provision of novel means to produce rectangular electrical pulses.

The invention also provides means to vary the time duration of the electrical pulses at any one pulse repetition frequency.

A further object of the invention resides in the provision of automatic pulse width limiting means such that the generated pulses may be less than, equal to, but of no longer time duration than approximately one half of the chosen pulse repetition period.

It is also an object of the invention to provide a system of primary and secondary oscillators wherein stabilized pulses are produced as to frequency of repetition and pulse duration and in which the repetition frequency is variable without affecting the stabilization.

Another object of the invention is to provide circuit means acting to insure that the spacing between successive generated pulses is independent of the mark-space balance of the source of oscillations.

Still another object of the invention resides in the provision of means for supplying successions of pulses having harmonically related repetition frequencies at a plurality of output terminals.

Another feature of the invention resides in the provision of start and stop means acting to start the system in such a manner that a predetermined sequence of pulses is obtained at the various output terminals.

Another feature of the invention resides in the provision of switching means excited by an oscillator operating at a fundamental frequency and controlled by a sub-harmonic oscillator to alternately produce on separate output terminals pulses occurring at the fundamental frequency repetition rate.

Other objects of the invention will be pointed out in the following description and claims and illustrated in the accompanying drawings, which disclose, by way of example, the principle of the invention, and the best mode which has been contemplated of applying that principle.

In the drawings:

Figs. 1 and 2 taken together form a circuit diagram of the invention.

Fig. 3 is a circuit diagram of a double stability trigger shown connected in block diagram form in Figs. 1 and 2.

Fig. 4 is a circuit diagram of an amplifier shown connected in block diagram form in Figs. 1 and 2.

Fig. 5 is a timing chart relating to the pulse

2

forms produced at various points in the circuit shown in Figs. 1 and 2.

Before proceeding to a detailed description of the invention, a brief description of the circuit abbreviations will be given.

In Fig. 3 there is illustrated a double stability trigger 1, of known type, comprising a pair of triode tubes 2, 3 (6J5 or 12SN7 twin type) having their plates and grids cross-connected by resistor-capacitor networks 4, 5; (200,000 ohms—100 micro-microfarads, respectively) tube 2 has a resistive connection 6 (200,000 ohms), between its control grid and a source 9 of bias voltage and also has a center-tapped plate load resistor 7 (20,000 ohms), connected to a source 9 of plate potential. Tube 3 has similar components respectively 8 and 9. Trigger circuit 1 is provided with a number of terminals each bearing a characteristic letter.

With the exception of terminals *a* and *h* which are shown capacitively coupled by means of condensers 10 (40 micro-microfarads) to grid circuits, and which are considered solely as input terminals; the terminals *b* through *g*, and *cc* may be considered as either input terminals, connectable to other apparatus for the purpose of supplying signals acting to reverse the equilibrium status of the trigger; or as output terminals connectable to other apparatus operated under control of the trigger. Located underneath the cathode of tube 3 is a letter *X*, which letter is used to denote a normally conducting tube, and in the case of a trigger, to denote which tube is conducting in the normal equilibrium state.

Shown below the trigger circuit diagram is a lettered rectangle 1, which is equivalent to the above described trigger. Within the rectangle the lettered circles represent correspondingly positioned input, or input-output, terminals on the circuit diagram.

A detailed description of the system with reference to Figs. 1 and 2 is set forth below.

Numbered blocks 11, 12, 13, and 14 relate to pulse amplifiers, later to be described.

The novel system of generating pulses of selectable time duration employs a primary source oscillator 15 of the free-running multivibrator type having means 16 to vary the frequency of oscillations. Any of the known types of multivibrators constructed with especial regard to high frequency stability may be used, and the circuit arrangement thereof forms no part of this invention, hence the showing in Fig. 1 is diagrammatic.

The control grid of a slicing amplifier tube 17 is connected through voltage dividing means to a

plate of one of the two tubes constituting the free-running multivibrator 15. The voltage dividing means comprises a resistor 18 (240,000 ohms) shunted by a capacitor 19 (50 micro-microfarads) and a second resistor 20 (220,000 ohms) which is connected between the control grid of the tube and a source 98 of bias potential, here shown to have a voltage of -100 volts. The suppressor grid of tube 17 is connected to its cathode so that the control grid exercises complete control over the flow of current within the tube.

The following description will relate sometimes to positive, or mark, impulses and negative, or space, pulses. Pulses will be defined according to the direction of the voltage excursion at the plate of a tube at the time the pulse is produced. For example, should the voltage at the plate of a tube change from a low value to a value which is higher and then after a period of time change back to a low value, a positive, or mark, pulse would be produced. The converse would be true for the production of a negative, or space, pulse.

Hence, according to the above definition of pulses, the value of resistors 18 and 20 are chosen such that tube 17 will operate as an on-off device, being turned on by positive pulses and being turned off by negative pulses generated at the plate of one of the tubes comprising the free-running multivibrator.

Tube 17 operates as a slicing amplifier. A slicing amplifier is one which is adapted to accept a median part of a voltage alternation. It is well known that the voltage output of a multivibrator is not a rectangularly shaped wave having vertical sides and 90 degree corners. Therefore, if only a part of such a multivibrator produced wave, such as a slice through the middle, is accepted for amplification then a more nearly perfect rectangular wave may be produced from the slicing amplifier because a median slice taken from the multivibrator produced waves will have more or less vertical sides and the cut-off and saturation characteristics of the tube type used will contribute toward the production of approximately square cornered waves.

The mark and space pulses derived from the free-running multivibrator 15 are of such a magnitude that a very considerable overdriving of the control grid of the slicing amplifier tube is obtained. The overdriving may be considered to be both positive and negative with respect to the normally used grid operating voltages. If the slicing amplifier tube be of the 6SJ7 type, a grid potential of approximately minus 10 volts will achieve cut-off of substantially all anode current. In this application, the grid is given to a negative potential of approximately minus 28 volts during space pulses and to a positive potential of approximately plus 12 volts during mark pulses. As has been hereinabove explained, this means that a median slice of the multivibrator produced wave will be accepted for transmission through tube 17. Approximately square corners will be produced by tube 17 because that portion of the wave represented by plus 12 volts will be clipped or limited by the flow of grid current. The lower 18 volts below approximately minus 10 volts, being more negative than the grid cut-off voltage will likewise have little or no effect upon the resultant output wave. The squareness of the wave corners produced will, of course, be dependent upon the individual tube type and other circuit component values used and will not be

absolute 90 degree corners, although they will be substantially square.

The amplifier tubes in the present invention are operated according to the above outlined on and off grid overdriving principles.

The output of the tube 17 is transmitted through a voltage dividing means comprising a resistor 21, shunted by a condenser 22, and a resistor 23 to the control grids of two tubes 24 and 25, said control grids being connected in parallel by a wire 26 and each having series connected parasitic suppression resistors 27 and 28 (each 5,000 ohms). Tubes 24 and 25 serve to effect further shaping of the multivibrator produced wave into an essentially rectangular form and to invert the phase of the waves. Components 21, 22, and 23 have the same quantitative values respectively as components 18, 19, and 20.

The plate of tube 24 is connected over a wire 27 to a pulse differentiating network shown enclosed by a box 28. The plate of tube 25 is connected through voltage dividing coupling means comprising a resistor 94 of 510,000 ohms shunted by a condenser 95 of 50 micro-microfarads capacity, and a resistor 96 of 470,000 ohms to the grid of tube 29, which tube serves mainly as a pulse phase reversing means. The values of components 94, 95, and 96 are usually used in the voltage divider coupling means shown in this invention. The plate of tube 29 is connected via terminal 30 to a second pulse differentiating means 31.

A differentiating circuit as herein used serves to produce narrow impulses of very short time duration from rectangular waves. It will be noticed that the differentiating circuits enclosed by boxes 28 and 31 each contain a condenser, and a pair of resistances, for example, in box 31, a condenser 32 of 50 micro-microfarads capacity and resistors 33, 34, respectively, 200,000 and 51,000 ohms. For the purpose of illustration, box 31 is provided with a pair of input terminals 30 and 35 and a pair of output terminals 36 and 37. A rectangular wave produced by tube 29 will have in a cycle thereof a pair of discontinuities in the form of abrupt changes in voltage. These abrupt changes in voltage impressed upon the differentiating circuit between terminals 30 and 35 are followed by an exponential charging or discharging of condenser 32. The flow of current through resistances 33 and 34 during the charging or discharging time produces pulses of output voltage between the output terminals 36 and 37. The duration of the pulse can be made as short as is desired simply by making 32, 33, and 34 small in value. Because the input voltage is a periodic wave having discontinuities an output pulse is produced by the differentiating circuit at each discontinuity of input voltage.

The narrow pulses of short time duration produced by the two differentiating networks 28 and 31 are transmitted respectively to tubes 38 and 39. Because these tubes are both biased beyond the cut-off point, application of differentiating network produced negative going pulses will not render said tubes conductive and these negative pulses are hence eliminated. On the other hand, the amplitude of the differentiating network produced positive going pulses is sufficient to render the tubes conductive, producing at the plates thereof amplified inverted and shaped short duration negative going pulses.

In summary then, the pulses produced by the primary multivibrator 15, amplified and shaped by tube 17 are transmitted to two chains of tubes,

one chain comprising tubes 24 and 38, the other chain comprising tubes 25, 29, and 39. Each chain is provided with a differentiating circuit inserted immediately preceding the last named tubes such that the effect of the system thus far is to produce negative going pulses at the end of each chain, the pulses of the chain comprising tubes 24 and 38 originating from the positive going wave edge of a multivibrator half cycle, and the pulses of the chain comprising tubes 25, 29, and 39 originating from the negative going wave edge of the same multivibrator half cycle.

The plates of tubes 38 and 39 are respectively commoned with the plates of tubes 40 and 41 comprising a single stability multivibrator 42 of known type. This single stability multivibrator, or one-shot multivibrator as it is sometimes termed, is in a stable or reset state when tube 41 is conducting and when tube 40 is at cut-off. Normally tube 41 is conducting because its control grid is biased considerably above the cut-off value by its connection via resistors 43 and 44, respectively 2,000,000 and 200,000 ohms to a source of positive potential. Also, the low potential existing at the plate of tube 41 is applied over resistors 45 and 46, respectively 510,000 and 470,000 ohms, which form a voltage divider between said plate and a source 98 of bias potential, to the grid of tube 40 to maintain this grid at a potential more negative than the cut-off value.

The short duration pulses transmitted through tube 38 are applied to the plate of tube 40, or to the "turn-on" terminal of 42, and act to drive the single-stability multivibrator from its stable state to the unstable state by the release of a cumulative triggering action to render tube 40 conductive and tube 41 non-conductive. Immediately tube 40 becomes conductive the potential at the turn-on terminal drops from source potential to a potential determined by the tube and other circuit parameters. Condenser 47 of 100 micro-microfarads capacity then starts to discharge through resistors 48 (20,000 ohms), 43, and 44 and through tube 40 until the voltage at the grid of tube 41 approaches and starts to exceed cut-off potential in a positive direction whereupon a second triggering action is initiated to restore the multivibrator to its stable state. Condenser 47 recharges through resistors 43, 44, and 48 and over the grid-cathode path of tube 41 when the single stability multivibrator is in its stable state.

Continuous oscillation of the multivibrator is prevented because the bias voltages applied to the control grids are so proportioned with respect to the value of plate potential that oscillation is inhibited at the conclusion of each cycle of operation.

Resistor 43 is made variable so that the time constant of condenser 47 and resistors 43, 44, and 48 and the impedance of tube 40, taken in combination, may be varied to selectively produce variable restoring time durations of the multivibrator. The effect of this is the production of rectangular waves having selectively variable widths.

It has been pointed out hereinabove that the negative going pulses produced in the plate circuit of tube 38 occur one half cycle later in time than those produced by tube 38 with respect to the primary source of oscillations. The plate of tube 38 is connected by a wire 50 to the plate of tube 41 which tube is rendered conductive whenever the single stability multivibrator, or sec-

ondary source of oscillations 42, is resting in its stable equilibrium state. The point of connection between the plates of tubes 39 and 41 and the plate load resistor 49 (20,000 ohms) therefore is termed the "turn-off" terminal of the secondary source of oscillations. Because a circuit parameter of 42 is made variable, allowing for the production of variable time duration pulses therefrom, it is possible that one using the instant system of pulse generation could so adjust resistor 43 that pulses having a time duration longer than one-half cycle of the primary source of oscillations would be generated.

It is not desirable to allow this condition to exist, and accordingly, automatic means comprising the chain of tubes 25, 29, and 39, and including differentiating circuit 31 are provided and connected to the secondary source of oscillations such that the negative going pulses generated by said chain will act to positively reset the secondary source of oscillations from its unstable state to its stable state should self-restoring not have occurred within one half cycle of the primary multivibrator. Therefore, it will now be understood that given any particular frequency of oscillation of the primary source 15, the secondary pulse source 42 may be adjusted to generate pulses of the same frequency of oscillation having selectively adjustable time durations ranging from the minimum permitted by tube and circuit characteristics to a maximum no longer than the time consumed by one half cycle of primary source oscillation at the chosen frequency of oscillation. It will be understood that the balance of 15, that is, the ratio of mark to space impulses, will have no effect on the repetition frequency of 42.

Returning now to the plate circuit of tube 25 it will be noticed that the load resistor 51 of 20,000 ohms therefor has a center tap to which is connected a wire 52 leading to the input terminals *a* and *h* of a double stability trigger 53. Trigger 53 may be any suitable trigger having two stable equilibrium states, for example, the one disclosed in an application, Serial No. 569,992, filed December 27, 1944, Patent No. 2,536,955, by R. L. Palmer et al, and also shown in Fig. 3. A property of double stability triggers of the disclosed type is that with each negative going pulse applied to both input terminals *a* and *h* the trigger will reverse its equilibrium status. Hence, for each negative going pulse produced at the plate of tube 25 trigger 53 will reverse its state. The normal state of equilibrium of trigger 53 is arbitrarily chosen as that state in which the right-hand tube is conducting. This is indicated by the X inscribed in the trigger box, and by connection to other circuit elements, for example, tube 84 or switch 88, later to be described. Trigger 53 output terminal *c* is connected through voltage dividing means to the control grid of a coincidence mixing tube 54. Trigger 53 output terminal *f* is connected through other voltage dividing means to the control grid of another coincidence mixing tube 55. The suppressor grids of tubes 54 and 55 are connected in parallel and to the output, or turn-off, terminal of the secondary source of oscillations 42 through a voltage divider comprising resistors 102 and 103, respectively, of 680,000 and 330,000 ohms.

In its normal state of equilibrium terminal *c* of trigger 53 will be at plate source potential because the left-hand tube thereof is not conducting. This high potential then will be applied over the said voltage dividing means acting to

overcome the grid bias potential and to condition tube 54 for later operation by placing on its control grid a potential substantially above the cut-off value. Similarly, in the reversed state of equilibrium of trigger 53, terminal *f* will be at plate source potential to likewise condition tube 55, for later operation, by placing on its control grid a positive potential substantially in excess of the cut-off value. Because trigger 53 is reversed in status by each negative pulse produced by tube 25, or by multivibrator 15, it may be stated that tube 54 is conditioned for one multivibrator cycle while tube 55 is conditioned for the next such cycle.

As stated above, the output pulses produced by the single stability multivibrator are applied to the suppressor grids of both tubes 54 and 55. Each reversal of the single stability multivibrator acts to apply sufficient positive potential to overcome the suppressor grid bias voltage and to render one or the other of tubes 54 and 55 conductive depending upon the condition of their control grids. For example, with trigger 53 being in the equilibrium state shown in the drawing, a positive pulse applied from 42 to the suppressor grid of 54 will render this tube conductive to produce therefrom a pulse which will be termed an AP pulse. A pulse produced by tube 55 is termed a BP pulse. Therefore, since trigger 53 is alternated with each negative going pulse produced by the primary source 15, it will be understood that tubes 54 and 55 are alternately conditioned and that these alternately produce pulses AP and BP under the control of the secondary source of oscillations 42.

Amplifying means 11 and 12 are respectively connected by wires 56 and 57 passing through terminals 92a and 92b, respectively, to the plates of tubes 54 and 55 for the purpose of amplifying, shaping, and providing outputs of different impedance values for the AP and BP pulses. The circuit arrangement of amplifier 11 is shown in detail in Fig. 4, while amplifiers 12, 13, and 14 are shown diagrammatically as they all are substantially equivalent to amplifier 11. The operation of amplifier 11 will be described and it will be understood that the operation of amplifiers 12, 13, and 14 is similar thereto.

The plate of tube 54 is connected through the usual voltage dividing means to the grid of a tetrode tube 58 by wire 56. Tube 58 acts as an amplifier and phase reversing device. Tube 58 is a 25L6 beam power amplifier tube and its plate is connected over three separate wires 59, 61, and 63, respectively, to a coincidence mixing tube 60; through a voltage dividing means to another power amplifier tube 62; and to a coupling capacitor 64. Tube 62 is another beam power amplifier which has large power handling capabilities. The plate circuit thereof is provided with a tapped load impedance 65, the tap being connected to an output terminal 66 to which may be connected other devices requiring negative going impulses and which do not form a part of this invention. Coupling capacitor 64 is connected to a diode direct current restoring means 67 and to the control grid of a second power amplifier tube 68 similar to tube 62 in power handling capabilities. Tube 68 is connected as a cathode follower type of amplifier having an output terminal 69 connected to the cathode thereof. This type of amplifier is well known in the art and no explanation of the principles thereof need be given. The grid bias is supplied to tube 68 by resistors 99, 100, and 101, in combination. Resistor 101 has a D. C. restorer or

diode clamper 67 connected in parallel therewith operating according to known principles of operation such as may be found in a volume, Principles of Radar, by the Staff of the Radar School, Massachusetts Institute of Technology, Second Edition.

It has been above said that amplifier 12, connected by wire 57 to BP pulse tube 55 is equivalent to amplifier 11. Wire 70 connected thereto corresponds to wire 59a of amplifier 11 with the exception of being connected to a source of supply pulses of negative polarity instead of positive polarity impulses.

Amplifiers 13 and 14 are likewise equivalent to amplifier 11. Amplifier 14 however, does not have any output wire corresponding to wire 59a of amplifier 11. Also, as shown by the drawing, amplifiers 13 and 14 are provided each with only a single output terminal corresponding in impedance value to output terminal 69 of amplifier 11. Hence, the power amplifying tube corresponding to tube 62 of amplifier 11 is not present in amplifiers 13 and 14. The circuit arrangements of amplifiers 11, 12, 13, or 14 are not part of the instant invention and are described solely for the sake of completeness. Refer now to Figs. 1 and 2.

It was stated hereinabove that wire 59a is adapted to supply positive going AP pulses from amplifier 11 to the suppressor grid of a coincidence mixing tube 60 through the usual voltage dividing means. The control grid of tube 60 is connected, also through an appropriate voltage divider, to the *f* terminal of a double stability trigger 71. Terminals *a* and *h* of said trigger are connected by wire 70 to a source of negative going BP pulses acting to operate said trigger from one of its stable states to the other for each negative BP pulse received. The *d* terminal of trigger 71 is connected by wire 72 to the input *a* and *h* terminals of another double stability trigger 73. The normal stable states of triggers 71 and 73 are indicated by an X placed at the appropriate side thereof.

Since trigger 71 is alternated from one stable state to the other by each negative BP pulse, it will be appreciated that for every two such pulses this trigger will produce a negative pulse on its terminal *d* which is connected to trigger 73 terminals *a* and *h* thereby operating trigger 73 from one stable state to its other stable state. In other words, triggers 71 and 73 constitute a frequency dividing chain adapted to divide the frequency of occurrence of supplied BP pulses by 2 in the case of trigger 71, and by 4 in the case of trigger 73.

Because the control grid of coincidence mixing tube 60 is connected to output terminal *f* of trigger 71 said grid will operatively condition tube 60 for every odd numbered BP pulse. It will be recalled that the suppressor grid of said tube is conditioned by AP pulses and that a 180 degree phase difference exists between AP and BP pulses. Hence, tube 60 will be rendered conductive during the time of occurrence of every second AP pulse. The pulses produced by the coincidence mixing tube 60 will occur at half frequency, with respect to AP pulses, and are termed CP pulses. CP pulses are transmitted over a wire 74 from the plate of tube 60 to amplifier 13 wherein they are adequately amplified before being supplied to an output terminal 69c.

Terminal *f* of trigger 73 is connected to the control grid of another coincidence mixer 75 through the usual voltage dividing means. Since trigger 73 is alternated from one stable state to

the other by every second BP pulse, it will be appreciated that mixer 75 is operatively conditioned for operation prior to the occurrence of every fourth AP pulse. A wire 59b supplies positive going CP pulses from amplifier 13 through the usual voltage divider to the suppressor grid of mixer 75. Hence, mixer 75 is rendered conductive during the times of occurrence of every second CP pulse. The pulses produced by mixing tube 75 are termed EP pulses and are transmitted over a wire 76 to amplifier 14, hereinbefore described, which serves to amplify said EP pulses for use by outside devices.

The desired sequence of pulses from the various outputs 66a and 69a, 66b and 69b, 68c, 69d of the system is respectively AP pulses and BP pulses at fundamental frequency, CP pulses at $\frac{1}{2}$ fundamental frequency and EP pulses at $\frac{1}{4}$ fundamental frequency, in that order, see for example, Fig. 5. To secure such a sequence of pulses, switch controlled discharge means are employed to reset triggers 53, 71, and 73 to their stable state shown. Also, it is essential that the primary source oscillator start with a positive going pulse for the reason that trigger 53 must remain in this state in order that the first pulse produced by the secondary source of oscillations under the control of the primary source of oscillations be effective upon mixer 54 to produce therefrom an AP pulse.

The pulse generating system is provided with a pair of switches 77 and 78, respectively Stop and Run. One terminal of each switch is connected to a source of positive potential, the other terminal of switch 77 being connected through a resistor to one grid of a double stability trigger 79; the other terminal of switch 78 also is connected through a resistor to the other grid of said trigger. Operation of either switch imposes high potential on the respectively connected grid for effecting reversal of the trigger to one or the other of its stable states. In Fig. 1, switch 77 is shown closed thereby maintaining trigger 79 conductive in its left-hand tube. Operation of switch 78, which is mechanically interconnected with switch 77, acts to open switch 77 and close switch 78 to place positive potential upon the right-hand grid of the trigger reversing same from left-hand conduction to right-hand conduction. The c terminal of trigger 79 is connected over the usual voltage dividing means to the control grid of tube 80.

When trigger 79 rests in the normal stable state of equilibrium, switch 77 closed, the potential at trigger terminal c is depressed and tube 80 is not conducting. When switch 78 is controlling the trigger the potential at terminal c is equal to that of the source of potential and tube 80 is rendered conductive.

The grid of a triode tube 81 is connected through the usual voltage dividing means to the plate of tube 80. When tube 80 is conducting plate current the potential at the plate thereof is depressed; which potential acts in combination with the voltage divider, and bias potential source to impress a bias potential upon the grid of tube 81 substantially more negative than the cut-off value. On the other hand, when tube 80 is non-conductive, tube 81 is rendered conductive. The plate of tube 81 is parallel connected with the plate of one of the tubes comprising the primary free running multivibrator 15, said plate being the pulse output terminal thereof. The pulse output tube plate of multivibrator 15 and the plate of tube 81 thus have a

common load resistor 82. Whenever tube 81 is rendered conductive, current flow through resistor 82 reduces the potential existing at the said pulse output terminal to such a value that the amplitude of the oscillations produced by multivibrator are insufficient to effectively excite the grid of slicing amplifier tube 17. Hence, for all effective purposes multivibrator 15 can be said to be turned off whenever switch 77 is closed. The instant tube 81 is rendered non-conductive by the means hereinabove set forth, the potential existing at the said pulse output terminal will make a positive excursion to start the system output pulse sequence with an AP pulse.

With respect to the cancelling of triggers 53, 71, and 73 to their normal states shown, both switchable means and electron discharge means are shown.

Because of the requirements of apparatus connectible to the pulse generating system, said apparatus forming no part of the present invention, it is preferred that switchable means, first named, be used to normalize triggers 53, 71, and 73. However, in other cases of use it is convenient to be able to start and stop the system by using only a single switch (such as switch 77-78) and accordingly a trigger normalizing means comprising a pair of tubes 83 and 84 is shown as a modification.

Changeover between the two modes of trigger cancellation is effectuated by means of a group of connections shown dotted on the diagrams. The connections labelled 85a and 85b relate to the usually used switchable means, while the connections labelled 86a, 86b, and 86c relate to the modification means.

Referring to Fig. 3 and to triggers 53, 71, and 73 in Fig. 2, it is to be noted that wire 87 connecting terminal cc with a -100 v. source of bias potential is to be disconnected. With connections 85a, 85b made, Fig. 2, and the 86a, 86b, and 86c connections disabled, terminals cc on all triggers 53, 71 and 73 are connected to one terminal of a normally closed push-operated switch 88. The other terminal of said switch is connected through a resistor 90 to a source of biasing potential. Assume for the moment that multivibrator 15 is stopped at time t shown by a vertical line 89 in Fig. 5. At this time, triggers 53, 71, and 73 are all in their stable state other than the normal state. Operation of switch 88 breaks the connection between terminals cc; leading through resistors 90 and individual trigger resistors 6 or 8, as the case may be, to the selected grids and the source of biasing potential. In effect, bias voltage is totally removed; permitting the grid to lose control of tube conduction; such action initiates a cumulative triggering operation to render the selected trigger tube conductive and thereby reset the triggers to their shown normal stable state.

Now treating the modification means; connections 85a and 85b are disabled and connections 86a, 86b, and 86c made. Hereinabove it was explained that whenever switch 77 was closed, tube 80 would be rendered non-conductive and that tube 81 would be rendered conductive. The control grid of tube 83 is also connected to the plate of tube 80, and similar to tube 81 is controlled by the tube 80 such that when 80 is non-conductive, tube 83 is rendered conductive. The plate of tube 83 is capacitively coupled to the grid of tube 84, said grid also having a resistive connection 91 of 510,000 ohms to ground potential. The cathode of tube 84 is connected directly to a

minus 100 volt source of potential. The plate of tube 84 is connected, via the removable connections 86a and 86b to the terminals cc of all the triggers 53, 71, and 73.

In operation tube 84 is effective to normalize triggers 53, 71, and 73 whenever the stop switch 71 is closed and run switch 78 is opened. Operation of said switches reverses trigger 79 producing therefrom on terminal c a negative going pulse. Said pulse, of indefinite duration, renders tube 80 non-conductive, the rise in plate potential thereof being transmitted via connection 86c to the grid of tube 83 to render said tube conductive. The negative change in plate potential, with respect to the plate of tube 83, is transmitted over wire 93 and through capacitor 91 (500 micro-microfarads) to the grid of tube 84, normally conductive, and is effective to momentarily render tube 84 non-conductive. Refer now to both Figs. 2 and 3. The plate of tube 84 is connected to all trigger terminals cc. Because wire 91 is disconnected in triggers 53, 71, and 73 it becomes evident that the plate load impedance for tube 84 comprises the three resistors, for example in Fig. 3, 8, 5, and 7 series connected in each trigger between terminal cc and the positive 150 volt source and parallel connected between the three triggers. Hence, the positive pulse produced by making tube 84 become momentarily non-conductive is applied to the respective trigger grids rendering the affected trigger tubes conductive and reversing the said triggers to their shown normal state.

While there have been shown and described and pointed out the fundamental novel features of the invention has applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. An electrical impulse producing system having a plurality of output terminals, a source of impulses occurring at a fundamental repetition frequency, impulse counting means comprising a cascade connected chain of triggers which is responsive to said source of impulses and acting to count a succession of impulses relative to said source of impulses, and coincidence mixing means adapted to be controlled by impulses arising from said source and said counting means for the production of impulses of predetermined equal widths and of different repetition frequencies at each of said plurality of output terminals.

2. In a system of the character described, in combination, primary source means for generating electrical waves of substantially square shape, secondary means driven by said primary source means for generating electrical waves of selectable mark and space relation, pulse shaping means coupling said primary source means and said secondary means and responsive to the primary source means for operating the secondary means through a secondary wave cycle, a pair of output terminals, and a pair of mixing means each operatively controlled by said primary source means for transmitting successive impulses generated by said secondary means alternately to said output terminals.

3. In a system of the character described, in combination, selectively variable frequency primary source means for generating electrical

waves of unequal mark and space relationship, secondary means driven by said primary source means for generating electrical waves of adjustable mark and space relation at a frequency determined by said primary source means, pulse shaping means coupling said primary source means and said secondary means for initiating the operation of the secondary means through a secondary wave cycle, other pulse shaping means responsive to said primary source means acting to limit the maximum time duration of the mark impulse generated by said secondary means, a pair of output terminals, and a pair of coincidence mixing means each of which is responsive to alternate wave cycles generated by said primary source means for transmitting successive impulses generated by said secondary means alternately to said output terminals.

4. An electrical impulse producing system comprising, primary oscillation means of the multivibrator type for generating electrical waves of substantially rectangular shape, secondary oscillation means comprising a single stability multivibrator, pulse shaping means responsive to said primary oscillation means in each wave cycle thereof for operating the secondary oscillation means through a secondary wave cycle, a double stability trigger which is operable to different ones of either of two sustained electrical on and off states and responsive to successive wave cycles generated by said primary oscillator means to shift its state once for each primary wave cycle, and a pair of electron discharge tubes each of which has first and second grids for exercising control over the electron stream therein, said first grids being connected to said double stability trigger for deriving control potentials therefrom and said second grids being parallel connected to said secondary oscillation means for deriving a control potential therefrom whereby said pair of electron discharge tubes are alternately responsive to successive wave cycles generated by said primary oscillation means for transmitting successive impulses generated by said secondary oscillation means.

5. An electrical impulse producing system comprising a multivibrator for generating electrical waves of substantially square shape, a first trigger which is operable to different ones of either of two sustained electrical on and off states and responsive to successive wave cycles generated by said multivibrator to shift its state once for each wave cycle thereof, a start and stop switch, a second trigger which is operable to different ones of either of two sustained electrical on and off states responsive respectively to the start and stop positions of said switch, and discharge means for applying signals representative of the on and off states of said second trigger to said multivibrator and to said first trigger to cause the multivibrator and the first trigger to stop and start synchronously in a chosen relationship.

6. An electrical impulse producing system for generating a succession of electrical impulses of predetermined width and predetermined spacing at predetermined repetition frequencies including a source of oscillation, a plurality of output terminals, a cascade connected chain of triggers, each operable to different ones of either of two sustained electrical on and off states and responsive to said source of oscillations, a plurality of coincidence mixers each responsive to a different trigger in said chain of triggers and to said source of oscillations for transmitting successive impulses from said source of oscillations

to said output terminals in a predetermined progression.

7. An electrical impulse producing system comprising a multivibrator for the production of a succession of electrical impulses occurring at a selectable predetermined frequency, a pulse differentiating circuit responsive to said succession of electrical impulses for producing sharp short time duration impulses therefrom, a single stability multivibrator having a normally inactive status and an active status from which it is self-restoring to its inactive status and responsive to the impulses produced by said differentiating circuit, variable resistance means for adjustably timing the duration of the active status of the single stability multivibrator, a double stability trigger which is operable to different ones of either of two sustained electrical on and off states and responsive to the succession of electrical impulses produced by said multivibrator, a first pair of coincidence mixers each having first and second grids for controlling the respective electron streams therein, said first grids being connected to said double stability trigger for deriving control potentials therefrom and said second grids being parallel connected to said single stability multivibrator for deriving a control potential therefrom and alternately responding to the successive impulses generated by said multivibrator at its predetermined repetition frequency for transmitting successive spaced impulses generated by said single stability multivibrator, a pair of pulse shaping amplifiers each respectively responsive to the impulses produced from said first pair of coincidence mixers, a cascade connected chain of double stability triggers responsive to the impulses produced by one of said pair of pulse shaping amplifiers, and a second pair of coincidence mixers each responsive to a different trigger in said chain of triggers, and one of said mixers being responsive to one of said pulse shaping amplifiers, the other mixer being responsive to the output of the last named mixer, whereby a progression of impulses of predetermined widths and spacings at predetermined frequencies are produced from said pair of pulse shaping amplifiers and said last named coincidence mixers.

8. An electrical impulse producing system having a plurality of output terminals comprising, in combination, a source of oscillations occurring at a selectable frequency, means comprising a plurality of double stability triggers connected in cascade responsive to said source of oscillations and adapted to generate a plurality of sub-harmonic repetition frequencies, coincidence mixing means responsive to both said source of oscillations and to impulses generated by one of said plurality of double stability triggers, and a plurality of other coincidence mixing means adapted to be connected to said output terminals each of which is responsive to the impulses generated by different ones of said plurality of double stability triggers and to the output impulses produced by a mixer under control of a double stability trigger producing impulses having a repetition frequency of $2f$ where f is the pulse repetition frequency of impulses produced by any of the plurality of coincidence mixers, whereby a predetermined progression of trains of impulses related one to another by integral phase and frequency ratios are produced at said output terminals.

9. An electrical impulse producing system comprising a multivibrator for generating electrical

waves of substantially square shape, a first trigger which is operable to different ones of either of two sustained electrical on and off states and responsive to successive wave cycles generated by said multivibrator to shift its state once for each wave cycle thereof, a start and stop switch, a second trigger which is operable to different ones of either of two sustained electrical on and off states responsive, respectively, to the start and stop positions of said switch discharge means for deriving and applying signals representative of the on and off states of said second trigger to said multivibrator and to said first trigger to cause the multivibrator and the first trigger to stop and start synchronously in a chosen relationship, a pulse differentiating circuit responsive to said succession of electrical impulses for producing sharp short time duration impulses therefrom, a single stability multivibrator having a normally inactive status and an active status from which it is self-restoring to its inactive status and responsive to the impulses produced by said differentiating circuit, variable resistance means for adjustably timing the duration of the active status of the single stability multivibrator, a first pair of coincidence mixers each having first and second grids for controlling the respective electron streams therein, said first grids being connected to said first double stability trigger for deriving control potentials therefrom and said second grids being parallel connected to said single stability multivibrator for deriving a control potential therefrom and alternately responding to the successive impulses produced by said multivibrator at its predetermined repetition frequency for alternately transmitting successive spaced impulses generated by said single stability multivibrator, a pair of pulse shaping amplifiers each respectively responsive to the impulses produced from said first pair of coincidence mixers, a cascade connected chain of double stability triggers responsive to the impulses produced by one of said pair of pulse shaping amplifiers, and a second pair of coincidence mixers each responsive to a different trigger in said chain of triggers, one of said mixers being also responsive to one of said pulse shaping amplifiers, the other mixer being also responsive to the output of the last named mixer, whereby a progression of impulses of predetermined widths and spacings at predetermined frequencies are produced from said pair of pulse shaping amplifiers and said last named pair of coincidence mixers.

10. An impulse producing system comprising, in combination, a variable frequency multivibrator adapted to generate electrical waves of approximately equal mark to space ratio at a fundamental repetition frequency, a single stability multivibrator adapted to generate electrical waves of variable mark to space ratio and responsive to said waves of equal mark to space ratio, a double stability trigger which is operable to different ones of either of two sustained electrical on and off states and responsive to said waves of equal mark to space ratio for producing impulses at a submultiple repetition frequency, and a pair of coincidence multi-grid mixers adapted to respond to the variable mark to space ratio waves of fundamental repetition frequency produced by said single stability multivibrator and to impulses of sub-multiple repetition frequency produced by said double stability trigger for the production of two trains of pulses

alternately occurring at said fundamental repetition frequency.

11. An impulse producing system comprising, in combination, a variable frequency multivibrator adapted to generate electrical waves of approximately equal mark to space ratio at a fundamental repetition frequency, a single stability multivibrator having a normally inactive status and an active status from which it is self-restoring to its inactive status and adapted to generate electrical waves of variable mark to space ratio responsive to said waves of equal mark to space ratio, a first double stability trigger which is operable to different ones of either of two sustained electrical on and off states and responsive to said waves of equal mark to space ratio for producing pulses at a sub-multiple repetition frequency, a pair of coincidence multi-grid mixers responsive to the variable mark to space ratio waves of fundamental repetition frequency and to the sub-multiple repetition frequency impulses for the production of two trains of impulses alternately occurring at said fundamental repetition frequency, a start and stop switch, a second double stability trigger which is operable to different ones of either of two sustained electrical on and off states responsive, respectively, to

the start and stop positions of said switch, electron tube discharge means for deriving and applying signals representative of the on and off states of said second trigger to said multivibrator and to said first trigger to cause the multivibrator, the first trigger and the pair of coincidence mixers to be started and stopped synchronously in a chosen relationship for the production of a predetermined progression of the alternately occurring two trains of impulses occurring at said fundamental repetition frequency from said pair of coincidence mixers.
